MACHINE FOR MAKING NECKTIES

Max M. Newman, New York, N. Y., assignor to
 American Machine & Foundry Company, a
 corporation of New Jersey

Application April 28, 1938, Serial No. 204,772

5 Claims. (Cl. 112—152)

My invention relates to improvements in a machine for making neckties.

One of the objects of my invention is to provide a machine whereby the lining of a necktie can be sewed to its outer material.

Another object of the invention is to provide reliable and simple guide means for feeding the lining and the outer material of the necktie to the stitching mechanism.

Another object of the invention is to provide improved means which can be used in combination with an ordinary sewing machine, or in combination with the machine illustrated in U. S. Patent No. 2,098,009.

Another object of the invention is to provide guide means which will be shifted automatically in accordance with the tapered shape of the necktie.

Other objects of the invention will be stated in the following description and drawings which illustrate preferred embodiments thereof, it being understood that the above statement of the objects of the invention is intended generally to explain the same without limiting it in any manner.

Fig. 1 is a top plan view of the improved device.

Fig. 2 is an end elevation of Fig. 1.

Fig. 3 is a sectional view, partially in elevation, on the line 3—3 of Fig. 1.

Fig. 4 is a development in plan view of the control cam which is shown in Figs. 1 and 2.

Fig. 5 is a top plan view showing another embodiment of the invention.

Fig. 6 is an end elevation of Fig. 5.

Fig. 7 is a sectional view on the line 7—7 of Fig. 5.

The machine comprises a drive shaft 1, which is driven by any suitable gear or by any other means. This drive shaft 1 passes through a wall of the U-shaped table or frame 4 of the machine. An ordinary bearing member 5 is provided in said wall. The frame is connected to any suitable support, by means of members 6. The shaft 1 is also mounted in supplemental angular bearing members 3, which are connected to the top wall of the frame 4.

A cam 2, having a hub 7, is mounted upon the shaft 1, so that said cam 2 and the shaft 1 turn in unison. Spacing bushings 8 are provided between the hub 7 and the bearings 3. A guard 9, which is connected to the top plate of the frame 4, is located below the bottom of the cam 2 so as to prevent the lining L and the tape S from contacting with said cam.

A guide 10 is also connected to the underside

of the top wall of the frame 4. This guide 10 has a channel-shaped portion 11, which serves as a guide to feed the strip of tape S.

The top wall of the frame is provided with a slot 12, which extends inwardly from one of the longitudinal edges of said top wall. Guide levers 14 and 15 are pivotally connected to the top wall of the frame 4, by means of pins 14a and 15a. These guide levers 15 have the angular shape shown in Fig. 3. Each of said guide levers has a straight leg which is located close to the underside of the top wall of the frame. Each of said guide levers also has an inwardly bent portion B which contacts with the respective edge of the cam 2.

As shown in Fig. 3, the tapered lining L, together with the tape S, are fed upwardly through the slot 12. The spacing ends or outer ends of the guide rods 14 and 15 are automatically spaced so that the distance between the outer ends of said rods 14 and 15 is substantially equal at all times to the width of the tapered lining strip L.

The channel-guide 11 also enables the operator to guide the movement of the strip S so that its longitudinal axis at all times coincides with the longitudinal axis of the tapered lining L.

Tension springs 18 hold the bent end B of the guide rods 14 and 15 against the edges of the cam 2. Said cam is shaped so that the distance between the outer ends of the guide rods 14 and 15 is at all times equal to the respective width of the lining L.

As shown in the development of the cam in Fig. 4, said cam has a substantially uniform tapered shape between the lines which are identified by reference numerals 19 and 20. The cam has a portion between the lines identified by reference numerals 20 and 21, which is of uniform width, as indicated in Fig. 2. The remaining portion of the cam, between the lines identified by reference numerals 21 and 22, is tapered, its taper being opposite to that portion of the cam which is between the reference numerals 19 and 20.

The shape of the lining L of the necktie is indicated in broken lines in Fig. 4. It can be seen that the taper of the tapered portions of the cam is opposite to the taper of the corresponding portions of the lining.

The lining L has two oppositely tapered end portions and an intermediate portion of uniform width. It will be noted that the distance between the outer ends of the guide rods 14 and 15 is greatest, when the inner ends of said guide rods contact with the narrow portion of the

cam. The relative opposite tapers of the cam and of the lining causes the proper guiding of the lining strip L.

In the embodiment shown in Figs. 5-7, the frame 4 is substantially the same as in the first embodiment. A drive shaft 1a is provided with internally threaded portions 24 and 25, which are oppositely threaded, and with an intermediate integral portion 29. The drive shaft 1a is turnably connected by means of a pivot screw 26 to one of the vertical walls of the frame 4.

A bearing washer 27 is provided between the head of the screw 26 and the adjacent vertical wall of the frame 4. Collars 30 are slidably mounted upon the member 29, and compression springs 31 keep the collars 30 at the outer ends of the members 29.

A collar 32 is located intermediate the springs 31. Said collar 32 is connected to the member 29 by means of a fastening member 33. Guides 28 and 28a having tapped bores, are mounted upon the members 24 and 25. These guides have planar faces which abut the adjacent planar surface of the top wall of the frame 4.

Therefore when the shaft 1a is turned, the guide members 28 and 28a are moved transversely towards each other or away from each other, depending upon the direction of revolution of the shaft 1a.

The speed of turning of the shaft 1a is regulated by any suitable manual or automatic means, so that the distance between the guides 28 and 28a is at all times equal to the width of the lining strip L.

The guides 28 and 28a are prevented from moving off the threaded members 24 and 25, by means of the collars 30. The guides 28 and 28a are made sufficiently wide so that they are held upon the threaded members 24 and 25 when said guides 28 and 28a abut the collars 30.

The device herein is an improvement upon the device originally described in application Ser. No. 143,708 filed in the United States Patent Office on May 20, 1937, and later covered by the continuation-in-part application, Serial No. 343,515, filed July 2, 1940, to take the place of the originally filed application, to which reference can be made for further details.

The folded outer material T of the necktie is led over the top wall of the member 4, the sewing operation being similar to that shown in Fig. 7 of the aforesaid application Ser. No. 343,515.

As the lining L passes through the slot 12 from the underside of the top wall of the frame, to the top surface of said top wall, the forward feeding movement of the lining strip is guided accurately by the guiding ends of the rods 14 and 15. If the operator feeds the strip S forwardly so that it is maintained straight, the channel member 11 maintains the strip S in proper position relative to the lining L.

For convenience in describing the invention in the claims, it is assumed that the plane of the top wall of the frame 4 is horizontal. However, this is immaterial for the purposes of the invention.

The shaft 1 can actuate suitable feed-mechanism such as feed rolls or the like, for feeding lining L, strip S, and material T automatically to the stitch-forming mechanism.

The invention above described may be varied in construction within the scope of the claims, for the particular device selected to illustrate the invention is but one of many concrete embodied-

ments of the same. The invention therefore is not to be restricted to the precise details of the structure shown and described.

I claim:

5. In combination, a plate, a strip-guide connected to said plate and depending therefrom, said plate having a lateral slot, a shaft located below said plate and having a cam fixed thereto, said cam being located below said plate and being also located intermediate said strip-guide and said slot, a pair of levers located at the underside of said plate and pivoted to said plate by separate pivot members, said levers having portions thereof adjacent said slot to act as a guide for feeding material of non-uniform width through said slot, said levers having portions thereof contacting with said cam.

2. Guiding mechanism for use in the fabrication of neckties of the type including an inner tape, a tapered intermediate lining strip, and a facing of necktie material, the final product constituting a necktie tapered from a wider portion at each end toward a common intermediate relatively narrow portion; said mechanism comprising in combination a plate having a slot, tape guide means disposed below said plate above the path of said tapered lining strip and adapted to guide said inner tape in substantially a fixed path below said plate and into a position associated with said tapered lining strip such that said associated tape and strip will advance in assembled relation through said slot into the path of said facing material above the plate, a pair of lining guide means movable into position to be engaged with the lateral edges of said lining strip adjacent to said plate-slot as said assembly is fed therethrough, means to bias said guides apart yieldingly in opposite directions with reference to the mid-line of said tapered lining strip, and means to move said last-named guides positively in opposite and equal directions with reference to said mid-line, and in correspondence with the taper of said edges.

3. Guiding mechanism for use in the fabrication of neckties of the type including an inner tape, a tapered intermediate lining strip, and a facing of necktie material, the final product constituting a necktie tapered from a wider portion at one end toward a relatively narrow portion; said mechanism comprising in combination a plate having a slot, tape guide means disposed below said plate above the path of said tapered lining strip and adapted to guide said inner tape in substantially a fixed path below said plate and into a position associated with said tapered lining strip such that said associated tape and strip will advance in assembled relation through said slot into the path of said facing material above the plate, a pair of lining guide means movable into position to be engaged with the lateral edges of said lining strip adjacent to said plate slot as said assembly is fed therethrough, and means to move said last-named guides laterally toward a predetermined point of said slot and away from a predetermined point of said slot, in correspondence with the taper of said lining, said slot extending along an axis substantially at right angles to said paths, and having an end opening to pass said tape and strip into the slot, or out of the same, laterally, at the side of the table.

4. Guiding mechanism for use in the fabrication of neckties of the type including an inner tape, a tapered intermediate lining strip, and a facing of necktie material, the final product

constituting a necktie tapered from a wider portion at one end toward a relatively narrow portion; said mechanism comprising in combination a plate having a slot, tape guide means disposed below said plate above the path of said tapered lining strip and adapted to guide said inner tape in substantially a fixed path below said plate and into a position associated with said tapered lining strip such that said associated tape and strip will advance in assembled relation through said slot, into the path of said facing material above the plate, a pair of lining guide means movable into position to be engaged with the lateral edges of said lining strip adjacent to said plate-slot, as said assembly is fed therethrough, and means to move said last-named guides symmetrically and laterally toward a predetermined point of said slot, in correspondence with the taper of said lining, said guides being retractable to clear the slot for insertion and withdrawal of said tape and/or lining strip sidewise at will, said means for moving the guides including spring means to bias said guides normally to said retracted position clearing said slot, and a cam device rotated by a cam-shaft to cause approach of said guides to guiding position adjacent to said slot, against said spring action.

5. Guiding mechanism for use in a sewing machine for the fabrication of neckties of the type including an inner tape, a tapered lining strip and a facing strip of necktie material, the final

product constituting a necktie tapered from a relatively wide portion at each end toward a common intermediate relatively narrow portion; said guiding mechanism comprising in combination a supporting structure having an aperture through which said tape and tapered lining are fed into alignment with said facing strip to be stitched together, tape guide means disposed below said supporting structure adapted to guide said inner tape in a substantially fixed path into a position associated with said tapered lining strip such that said associated tape and tapered lining strip will advance in assembled relation through said aperture into the path of said facing material above said supporting structure, a pair of lining guide means disposed below said supporting structure and movable into position to be engaged with the lateral edges of said tapered lining strip without folding over the edges of the same; and means constructed and arranged to cause equal and opposite movements of said guiding means against said lateral edges in conformity with the varying taper of said lining strip, and at each side of a stitching line following the mid-line of said lining strip, whereby said lining strip is guided constantly to present it in position for stitching of the facing material along the mid-line of the tapered lining strip, regardless of the extent and angle of taper of said lateral edges.

MAX M. NEWMAN.
